UNITED STATES PATENT OFFICE.

THOMAS JONES AND JACOB KIEFER, OF HIGHLAND, WISCONSIN.

CLOVER-HULLER.

SPECIFICATION forming part of Letters Patent No. 252,223, dated January 10, 1882.

Application filed June 11, 1881. (No model.)

To all whom it may concern:

Be it known that we, THOMAS JONES and JACOB KIEFER, citizens of the United States, residents of Highland, in the county of Iowa and State of Wisconsin, have invented a new and valuable Improvement in Clover-Hullers; and we do hereby declare that the following is a full, clear, and exact description of the construction and operation of the same, reference 5 being had to the annexed drawings, making a part of this specification, and to the letters and figures of reference marked thereon.

Figure 1 of the drawings is a representation of a longitudinal section of our invention, and Fig. 2 is a plan view of the same.

This invention has relation to clover-hullers; and it consists in the novel construction and arrangement of parts hereinafter fully described, and particularly pointed out in the 20 claims.

In the annexed drawings, the letter *a* represents the frame or casing of the huller, constructed and supported as usual. At one end, between the sides, is secured the concave case 25 *b*, open at the top, and having at its ends, on opposite sides, the recesses *b'*, forming openings into the case. This case is placed with a slight slant transversely of the frame or casing. Journaled within and lengthwise of this 30 case is the hulling or breaking roller *c*, provided with teeth *c'*. Journaled inside the frame or casing transversely, and close to case *b*, is the pressure-roller *d*.

Arranged within and lengthwise of the casing *a* is the riddle or shaker *e*, which is pivoted to rock-shafts beneath. This shaker has a slant downward toward the case *b*, and when in its lowermost position stops with its lower end just under the inner side of said case. The 40 top of the riddle consists of transverse parallel slats *f*, having a slant in the direction of that of the shaker, and forming intermediate spaces *g*. Reciprocating longitudinal movement is given to the shaker by any suitable means. At the lower end of the shaker we 45 securely fasten a screen, *k*, which is corrugated to fit the shaker-slats, and has at the bottom of its depressions *l* the perforations *m*, which latter, when the screen is in place, come over 50 the spaces, *g*. One corner, *n*, of the screen *k* is cut off obliquely, and along the edge thus

formed is secured a guide-board, *p*. This guide-board *p* has its outer and lower edge, *q*, situated close to the side of the casing or edge of the shaker and its other edge, *r*, near the middle of the screen. This guide-board *p* is located so as to slant from the middle of the screen down toward the lower end of said screen, so that it will direct the clover from the edge to the middle, as hereinafter described. 55 Only one guide-board is used, so as to leave a free passage beyond its inner end for the clover. For better security the guide-board has a rear brace, *s*.

As the clover passes from the case *b* it falls 60 on the screen-covered portion of the shaker. The roller *d* keeps the mass down on the shaker, spreading it over the latter, and the guide-board *p* directs it toward the middle of the screen, whereby the clover receives a thorough 65 sifting, the seed dropping through perforations *m*, and the cleaned heads pass off over the upper end of the shaker. The guide can be removed while thrashing other grain.

Hullers have been made with an oblique 70 guide attached to the side of the box and projecting over the screen or shaker, and a grain-separator has been patented having V-shaped deflecting flanges secured to the shaker for conducting the grain to the edge of the said shaker. 75 In our device the guide-board is fastened to the screen, moving therewith and preventing jamming, and extends toward the lower end of the shaker, from the middle to the edge, thereby conducting the clover toward the middle. 80

What we claim is—

1. In a clover-huller, the combination, with the hulling-cylinder *c* and concave *b*, the shaking-carrier, and the deflector or guide-board *p*, 90 of the intermediate pressure-roller, *d*, substantially as and for the purposes specified.

2. In a clover-huller, the combination of the hulling-cylinder *c* and concave *b*, adapted to discharge at one side of the shaker *e*, of the shaker *e*, the guide-board or deflector *p*, and the pressure-roller *d*, substantially as and for the purposes specified.

3. In a clover-huller, the combination, with the shaker *e*, having the open slotted surface, 100 of the corrugated riddle or screen adapted to fit upon said shaker and formed with perfora-

rations in the bottoms of the corrugations, substantially as and for the purposes specified.

4. In a clover-huller, the combination, with the slotted shaker and the corrugated screen applied to the upper surface thereof, of the guide - board *p*, secured to the said shaker at one side thereof and extending toward the middle of the screen, substantially as and for the purposes specified.

In testimony that we claim the above we to have hereunto subscribed our names in the presence of two witnesses.

THOMAS JONES.
JACOB KIEFER.
